Oscar Gell

UNITED STATES PATENT OFFICE.

JOSEPH J. LUTKIEWICZ, OF PERRYSBURG, OHIO.

OPERATING MECHANISM FOR CHURNS.

1,279,890.

Specification of Letters Patent. Patented Sept. 24, 1918.

Application filed April 26, 1917. Serial No. 164,680.

To all whom it may concern:

Be it known that I, JOSEPH J. LUTKIEWICZ, a subject of the Czar of Russia, resident of Perrysburg, county of Wood, and State of Ohio, have invented certain new and useful Improvements in Operating Mechanism for Churns, of which the following is a specification.

This invention relates to improvements in rotary churning, and has as its special object the provision of a churn which may be completely and readily disassembled for the purpose of cleansing or the like without the use of tools or appliances of any kind, the churn being of especially simple and practical construction, comprised of few and simple parts.

These objects are attained by the novel construction and combination of parts hereinafter described and shown in the accompanying drawing, forming a material part of this disclosure, and in which:

Figure 1 is a vertical sectional view taken through the center of the apparatus.

Fig. 2 is a top plan view of the cover and body, parts being broken away to show the interior.

Fig. 3 is a fragmental sectional view taken on line 3—3 of Fig. 2, and

Fig. 4 is a perspective view of the shaft support.

The apparatus consists of a cylindrical casing 10 having a solid bottom 11, the open top of the casing being normally covered by a cap 12 having annular flanges 14 engageable with the periphery of the vessel 10.

Vertically mounted in the vessel 10 is a shaft 18 having engaged at its lower end a hub 19, to which are secured a pair of oppositely disposed beater-blades 20 containing a plurality of apertures 21 in order to beat and commingle the material to be churned.

The shaft 18 is driven by a miter gear 24, rigid upon its upper extending end 25, the gear being driven by a miter pinion 26 secured upon the horizontal shaft 27, rotatably mounted in brackets 28 and 30, the latter of which is formed integrally with a transversely disposed plate 32 rigidly secured to the top of the cover 12 by means of screws 33 passing through the openings 34 formed therein.

The opposite end of the bar 32 is bent so

as to be turned reentrantly, extending past the center, forming an upper bearing 35 and containing an opening 36 registerable with the central passage 37 through which the shaft end 25 is rotatably mounted.

A pair of spring clips 40 are secured to the bar 32, the upper ends being beveled so that when the upper element 35 is turned downwardly, it is engaged by their hooked surfaces and held in position to aline the openings 36 and 37.

Motion is conveyed to the shaft 27 by means of the crank 44, provided with an operating handle 45, so that rotary motion is transmitted to the dasher plates or blades 20 when the churn is operated.

Obviously, when the cover 12 is removed the dasher blades and shaft are removed with it, allowing free access to the interior of the casing 10, and it will be obvious, if the spring clips 40 are withdrawn, the upper element 35 may be raised permitting the shaft 18 to be removed.

Having thus described my invention, what I claim as new and desire to secure by Letters Patent, is:

In a churn, the combination with a cover and a cylindrical vessel, a plate element consisting of a foot plate and a head plate bent back over part of said foot plate in spaced relation thereto and integral therewith, centrally secured to the cover, bearings formed on one end of said plate element, a horizontal shaft mounted therein, means for rotating said shaft, a pair of bevel gears, one of said gears being rigidly affixed on said horizontal shaft, a vertical shaft, the second bevel gear being attached at the upper end of said vertical shaft and meshing with the first named bevel gear, a second bearing for said shaft integrally formed with said plate element, and a pair of opening clips secured to the foot plate of said plate element, beveled fingers at the upper ends of said clips gripping over the upper edge of said head plate when the same is bent below the upper ends of said fingers for holding the vertical slots constituting the bearings for the upper end of the vertical shaft in plumb, substantially as described.

In testimony whereof I have affixed my signature.

JOSEPH J. LUTKIEWICZ.
